UNITED STATES PATENT OFFICE

JOSEPH F. JAWOROWSKI, OF CLEVELAND, OHIO, ASSIGNOR, BY DIRECT AND MESNE ASSIGNMENTS, OF TWO-NINTHS TO SAMUEL E. DETTELBACH, ONE-THIRD TO SAM W. EMERSON, AND ONE-NINTH TO EDGAR A. HAHN, ALL OF CLEVELAND, OHIO

ROTARY PUMP

Application filed December 31, 1927. Serial No. 243,810.

My invention relates to rotary pumps, and my object in general is to provide a double acting pump of simple construction capable of producing a uniform flow of liquid under constant pressure. Other objects are embodied in the details of construction substantially as hereinafter pointed out in the claims.

In the accompanying drawings, Fig. 1 is a side elevation of the pump, and Fig. 2 an end view thereof, Fig. 3 is a vertical section of the pump on line 3—3 of Fig. 1. Fig. 4 is a side elevation of the body of the pump, one side plate being removed. Fig. 5 is a sectional view on horizontal lines 5—5 of Fig. 4. Fig. 6 is a horizontal section of the upper part of the pump on line 6—6 of Fig. 4. Fig. 7 is a vertical section on line 7—7 of Fig. 2. Fig. 8 is a part section and elevation on line 8—8 of Fig. 7.

The pump comprises a main body 2 having a spreading base 3 to support the same in an upright position. The upper part of body 2 has an opening 4 extending entirely through the same from front to rear, and the lower part of the body is of circular shape and provided with a pair of circular working chambers 5 and 6 in axial alignment but spaced apart by a central division wall 7 in body 2. Oppositely extending bosses 8 and 9 on body 2 contain horizontal intake and discharge openings 10 and 11, respectively, which communicate with the top of both working chambers 5 and 6. A pair of reciprocable blades or movable abutment members 12 and 13 are confined within separate vertical slots or channels 14 and 15, respectively, intermediate the intake and outlet openings 10 and 11. The upper end 16 of each abutment member or blade is channeled lengthwise and extends into opening 4 in body 2, while the lower end 17 of each abutment member or blade is reduced in width or thickness and extends into its corresponding working chamber. These blades are held in constant working contact or engagement with a pair of rotatable piston or rotor members 18 and 19, respectively, which are keyed to a power shaft 20 having rotatable bearing in hubs 21 and 21' on the front and rear side plates 22 and 23, respectively. The pistons are circular and in the

main eccentric to the axis of shaft 20 and the working chambers to provide crescent-shaped working spaces which are divided or separated by the abutment blades when projected thereinto. However, a large sector 24 of each piston involving about ninety degrees of the circle is concentric with the axis so that it fits snugly the circular wall of the working chamber within which it rotates. Preferably, the concentric engaging surface 60 of each rotor is of such length as to fully cover both of the arc-shaped intake and outlet ports 25 and 26, respectively, when this part of the rotor is passing said ports and the abutment member is raised to its maximum height. 65 However, the intake and outlet ports 25 and 26 extend a short distance into the central wall of body 2 and also above the circle of movement of the concentric part of the rotor so that when the abutment blade is raised 70 to its maximum height a small area thereof will still remain exposed to the fluid openings especially when the rotor is still in a position to cut off all communication between the fluid openings and its working chamber. The 75 purpose of this working arrangement is to keep one side of the abutment blade exposed to the fluid under pressure so that the blade is pressed against one side wall of the slots, whereby leakage is prevented between the 80 inlet and outlet openings. A further advantageous result is obtained by the said arrangement whereby the fluid under pressure is transmitted to the upper end of the piston blade or abutment member and utilized to 85 press the blade constantly against the rotor. Thus the area of the top end of the blade is greater than the area exposed to the fluid at the lower end of the blade, and as the fluid under pressure acts to press the blade sideways in its slot and seat, one side or seat is sealed and the other or pressure side affords a slight space through which the fluid under pressure may pass upwardly into the top opening above the top edge of the blade. The 90 fluid pressure on the upper end of the blade holds the blade in working engagement with the rotor under normal operating conditions, but it is also desirable that a supplemental pressure be present on each blade, to facilitate 95 100

starting operations, to take up wear, to avoid loose play, and to effect a balancing equalizing movement between the pair of blades. The two eccentric rotors or pistons are keyed to the shaft one-hundred and eighty degrees apart or in balance, thereby promoting a constant uniform flow of fluid from the pump, and the respective piston blades or abutment members are engaged at their upper ends by the rounded extremities of a pivoted equalizing member or lever 29 which is spring-pressed. Thus the pivot pin 30 of lever 29 is removably seated within the slotted or forked extremity of a short cylindrical plunger 31 operating in a vertical opening 32 centrally at the top of body 2. The upper end of opening 32 is sealed by a hollow cap or nut 33 containing a spiral compression spring 34 which extends downwardly into a socket 35 in the upper end of plunger 31. A constant downward pressure is exerted by spring 34 upon equalizing lever 29 to hold the piston blades under control in starting the pump and at normal operating speeds, and obviously if wear takes place the spring compensates for such wear and avoids loose or idle play between the parts, the construction of the pump, as described also permits convenient assembly and disassembly of the parts.

The opposite ends of the piston shaft are reduced in diameter and one end is longer than the other. The short end of the shaft extends into one boss or bearing on the side plate and the shaft opening is closed and sealed by nut 36. The longer end of the shaft extends through a ring packing 37 and packing gland 38, and a clamping bar 40 having lugs 41 projecting into cross slots 42 in the gland. A pair of bolts 43 secure the clamping bar to the hub of the side plate. The pair of side plates are secured tightly to the opposite sides of the body by tie bolts 44. Removal of the side bolts permits the side plates to be detached from the body and then all the working parts therein are fully exposed and more readily removed and reassembled including the equalizing lever in the cross passage at the top of the body.

As constructed the pump is a reversible pump as well as a double-acting pump.

A vertically-inclined opening 45 is provided in the top of the pump body, which opening communicates with the cross passage 42 and a screw plug 46 closes the entrance to said bore or opening. Upon removing the plug a pipe connection may be made with a source of steam or other fluid under pressure and which fluid is delivered into the cross passage and thence through the slots and into the working chamber to the outlet side of the pump and also to the inlet side when not under pressure or when open to the atmosphere. The purpose of this arrangement is to permit the pump interior and the operating parts therein to be readily cleaned when

the pump is being used for pumping heavy liquids, paint, silicon-soda, etc.

What I claim, is:

1. A double-acting rotary pump, comprising a body having a pair of circular working chambers separated by a central division wall, said body also having an unobstructed cross passage at its top and vertical slots connecting said passage with said chambers, said body being further provided with separate inlet and outlet openings having ports communicating with said working chambers adjacent the slots, said ports being elongated and open at one end to the bottom end of said slots, a pair of rotatable pistons eccentrically mounted within said circular chambers having a peripheral sector thereof of substantial length engaging the circular walls of said chambers, a pair of piston blades slidably confined within said slots and engaging said pistons, an equalizing lever pivotally mounted within said cross passage and engaged at its opposite ends with said blades, and a compression spring for said lever to force said piston blades in self-adjusting contact with said pistons.

2. A rotary pump, comprising a body having a pair of circular working chambers, a cross passage at the top of said body, vertical slots connecting said passage with said chambers, separate inlet and outlet openings, communicating passages between said openings and said working chambers entering into said chambers adjacent said vertical slots, recessed areas in the wall portion of the working chambers embracing the communicating openings of said passages and said vertical slots with said working chambers, a pair of rotatable pistons eccentrically mounted within said working chambers and a pair of piston blades slidably confined within said slots and engaging said pistons.

In testimony whereof I affix my signature.

JOSEPH F. JAWOROWSKI.
